REMOTE AUTOMATIC RADIO CONTROL

Robert H. Hill, Anderson, and Bertram A. Schwarz, Kokomo, Ind., assignors to General Motors Corporation, Detroit, Mich., a corporation of Delaware

Application March 16, 1938, Serial No. 196,108

17 Claims. (Cl. 192—142)

This invention relates to automatic control apparatus and more specifically to means for automatically tuning a radio receiving set.

With the increased interest in the use of automotive radio receiving sets and also with the increased demand for some means in a household receiving set which would either tune the set automatically from a point adjacent the set itself or from some remote point, it has been found desirable to design mechanism to carry out this automatic control feature.

It is therefore the object of our invention to provide an automatic radio tuning device.

It is a further object of our invention to provide a remotely positioned automatic tuning device.

It is a still further object of our invention to provide an automatic remote tuning device which is simple and foolproof in its operation so that it may be easily operated.

With these and other objects in view which will become more apparent upon the disclosure of the following specification, our invention will be best understood by reference to the following specification and claims which are illustrated in the accompanying drawings, in which:

Figure 1 shows a schematic diagram of the general arrangement of our invention with relation to the radio set.

Figure 2 shows a wiring diagram of the circuit of our invention.

Figure 3 is a top plan view of the tuning device per se.

Figure 4 is a side elevation of the device shown in Figure 3.

Figure 5 is a sectional view taken on line 5—5 of Figure 4.

Figure 6 is a sectional view taken on line 6—6 of Figure 4.

Figures 7, 8 and 9 are views similar to Figure 6 showing the different positions of operation for the operating members.

Figure 10 is a side elevation of one of the operating relays.

Figure 11 is a top view of the same.

Figure 12 is a sectional view taken on line 12—12 of Figure 4.

Figure 13 is an enlarged sectional detail of the mounting of the gears on the shaft.

Figure 14 is an enlarged detail showing one of the operating switches.

Referring now more specifically to the disclosure of Figure 1, a radio receiving set designated generally at 2 is shown which is connected to a cable 4 to the opposite end of which is

connected the usual remote control panel 6 having therein a tuning knob 8, a volume control 10, and a tone control 12.

There is also associated with the set 2 a conventional form of speaker 14 and all of the apparatus so far described forming the conventional automotive set of the present day, the set being mounted on the dash of the car and the control panel being mounted on the instrument panel for access to the driver of the vehicle. 10

Extending from one side of the radio set is one end of the tuning shaft 16 to which is coupled by suitable coupling member 18 the tuning device generally designated at 20 which forms the main body of our invention. This tuning device is 15 connected by an electric cable 22 having a plurality of wires therein to a remote control panel generally designated at 24, said panel having a plurality of push button switches 26 therein, the closure of which causes the energization of an 20 associated magnet for tuning purposes. While this unit is shown as placed at a distance from the set, it of course may be located within the set casing if desired, as when it was used in a 25 household set.

The general operation of the automatic portion of the device is such that when one of the buttons 26 is depressed the tuning motor, switches and relays within the device 20 will be set in operation to cause the tuning shaft in the 30 radio set to be turned to a predetermined position for the reception of a particular station, the identification of which is marked on the labels 28.

The tuning device 20 is composed of two opposite spaced panels 30 which are secured together at the bottom by plate 32. Slidably carried between the spaced panels 30 at opposite ends of the device are two irregularly shaped plates 34 which extend upwardly above the edges of the panels 30 and have adjacent their upper portion two paired oppositely disposed openings 36 within which are carried longitudinally extending rods 38. These rods extend substantially the full length of the assembly and are held in position by having a groove 40 provided adjacent each end within which fits one end of a spring 42 so that the same may not be moved longitudinally from their supports but may move vertically slightly. 35

Outside of the members 34 are two end plates 44 which extend up to a slightly greater height than the members 34 and which have adjacent the central portion an opening 46 in each end in which is carried a rod 48, the outer ends of 50 55

which are each connected to a coil spring 50 which is anchored to the plate at a suitable position such as 52.

By reference to Figure 5 it will be seen that 5 the openings 46 in these end plates are considerably larger than the diameter of the rod 48 so that there may be some relative movement of the rod in the opening which of course is biased by the springs 50 to the lowermost position of the 10 aperture. On one side of the assembly there is provided an angled bracket 53 upon which is supported a small motor 54 which drives through its shaft 56 a suitable worm gear 58. There is supported in the assembly at right angles 15 to the motor shaft 56 a transverse shaft 60 having on its end a worm wheel 62 which is adapted to mesh with the worm gear 58 and transfer the power of the motor into the interior of the assembly. Each of the side panels 30 carries a 20 small upstanding bracket 64 in which the shaft 60 is journalled in any suitable bearings such as those illustrated at 66. Interiorly of the assembly on the shaft 60 is secured a gear 68 which is adapted to mesh with and drive a second gear 25 70 on a third shaft 72 which lies substantially parallel to the motor shaft 56 and is trunnioned in two vertical plates 74 within the assembly. This shaft 72 does not extend the full length of the distances between the relatively movable 30 plates 34 but has located on its inner end a circular plate 76 which has an eccentric projection 78 on its outer face which engages with a circular bearing 80 which extends into a slot 81 in the rear wall 34. The gear 70 also has an 35 eccentric projection 82 in alignment with the projection 78 which extends into a circular bearing 84 flanged to maintain it in slot 86 in the forward plate 34.

It is thus evident that as the shaft 56 is driven 40 by the motor the transverse shaft 60 will be rotated which will in turn drive the second longitudinal shaft 72 and rotate the gears 70 and 68 which through their eccentrics will cause the two opposite plates 34 to be moved up and down 45 carrying the associated assembly with them including the pair of longitudinal rods 38.

Mounted within the lower portion of the assembly and running longitudinally thereof and parallel with the shaft 72 is a further shaft 88 50 which is directly connected to the tuning condenser shaft of the set to which it may be connected by any convenient coupling such as 90. This shaft is also trunnioned in the same plates 74 by suitable bearings and is also supported adjacent its midpoint by a further plate 92 and has located thereon a series of gears 94, the 55 method of mounting the latter being best shown in Figure 13 where it will be seen that the shaft has countersunk grooves cut thereinto, such as 96, adjacent each end of each one of these gears 94 which are rotatably mounted on the shaft. There are inserted in these rings spring disks 98 which bear against the shoulders on the shaft and against the opposite faces of the gears 94 60 so that the same may be connected to the shaft frictionally but may have relative motion thereto where it is desired to fit them at some particular angularity with respect to the shaft for initial setting.

Supported adjacent the left end of the shaft 70 as viewed in Figure 4 is a suitable housing 100 in which is enclosed a magnetic coil 102 which surrounds a disk 104 supported on the end of the shaft in such a manner that when the magnet is energized the disk will be locked against 75

rotation and therefore lock the tuning shaft in that position. The purpose of this device is to allow initial setting of the mechanism to a predetermined station.

Supported on the brackets 74 and to the rear 5 of an insulating panel 106 carried thereby are a plurality of transversely positioned relay coils 108, one for each station and in this instance there are six. They are each located above the associated pinion 94. Slidably supported on the 10 side panels 30 adjacent each pinion are a pair of oppositely disposed racks 110 and 112 which are supported in such a manner that they may move up and down as shown and in so doing will rotate the associated pinion 94 and the shaft 88. 15 It will be seen from an examination of Figures 7, 8 and 9 that as the racks are set at different positions any pressure from the top will cause the pinion to rotate a predetermined amount until the two are leveled and in alignment and 20 the amount of difference may be on either side which will cause the rotation of the pinion and shaft in either direction. Therefore if we have the racks and pinion as shown in Figure 7 and 25 pressure is applied to the upper portion of the right hand rack, the pinion will be turned until the upper portions of the two racks are parallel which will be substantially three teeth on the pinion and at the setting will give some desired 30 station.

Carried on the longitudinal rods 38 are a 35 plurality of spaced pivoted arms 114 which are located in pairs forming what might be termed 40 tongs, two for each one of the magnets 108. These arms 114 are formed in the manner of a bell crank pivoted slightly off the center of the angle and having a counterbalancing heavier portion 116 to maintain them in their outward 45 position, the inner ends 118 being located to contact the rod 48 carried by the stationary end 50 portions. These members of course move up and down with the movable members 34 and when in their uppermost position contact the rod 48 to cause the tongs to move apart or assume the 55 position as shown in Figure 6. Upon an energization of one of the magnetic coils 108, the two attendant arms will be pulled together as soon as the end plates have started down and will allow such an action, and when in this position further movement of the arms downwardly causes engagement of the upper edge of one of the racks with one arm and forces the same down until the two are leveled which, due to the design of the apparatus, should be at the lowermost portion of travel of the end plates 34 60 which will then resume their motion in an upward direction and again come to rest in the uppermost position where the rod 48 will again force the tongs outwardly.

It may be mentioned here that the rods 38 are 65 smaller than the openings 36 in the end plates into which they fit and since they are held downwardly by springs such as 42 they may be pressed up a short distance and this spring biasing at the bottom of the travel of the end plates assures 70 that the racks be brought into correct alignment. Similar springs 120 are utilized upon a boss 122 on the arms 114 to prevent their swinging back and forth freely and to tend to cause them to assume the last position into which they have 75 been forced, either by the magnet or the mechanical means.

Mounted on one of the stationary end plates 44 80 is a bracket 124 upon which are disposed a plurality of spring contact members 126 separated 85

by insulating disks 128. The ends of the spring members carry switch contacts 130 and 132 as well as a spacing member 134 causing a cooperation between the two sets. The contact members project to a position adjacent a slot 136 in the plate 44 within which slot an extending pin 138 reciprocates vertically in synchronism with the rotation of the shaft 72 inasmuch as it projects from the vertically reciprocating plate 34. The object of this switching arrangement is to provide means for opening the speaker circuit when the automatic tuning means is energized and then causing said circuit to close when the automatic mechanism resumes its position of rest. This prevents any objectionable noise emanating from the loud speaker while the set is being tuned and it also operates a motor switch.

Figures 10 and 11 also illustrate a suitable relay coil 140 which is mounted on an insulating member 142 and which controls the operation of a motor switch 144 which is energized in series with any one of the magnets 108 to cause the motor to be energized when a given push button is depressed, and the associated tongs are drawn together so that the rack may be leveled.

Referring now specifically to Figure 2 which shows a circuit diagram of the various portions already described, the buttons 26, 26A, 26B, etc. are shown connected directly to one side of an incoming line 146 from any suitable source of supply. In series with each one of the buttons is one of the control magnets 108, 108A, 108B, etc. The opposite side of each of the series circuit is connected to a common lead 148 which is in turn connected to the motor relay 140, the opposite side of which is connected to ground.

The main power line 146 is connected to the motor switch 144, the same also being connected directly to line 150 and thence to the motor 54 and to ground which controls the operation of the motor. Line 146 is also connected to switch 130 which is on the bracket 124, the movable or common portion of said switch being connected as shown to line 150 by a short tap line 152. The switch 132 mounted on the same bracket is connected directly to the speaker. For setting purposes there is shown a setting button 154 which is connected to incoming line 146 and also through line 156 to the magnetic lock 102 and thence to ground.

The operation of the whole device is as follows:—Taking the device in its initial condition before any predetermined stations have been set thereon, the set is tuned manually to a desired station and then the locking switch 154 is depressed, energizing the magnet 102 to maintain the tuning shaft in that position. One of the buttons 26 is then depressed which energizes the associated magnet 108 and also the motor control magnet 140 through line 146, button 26, magnet 108, relay coil 140 to ground. This causes the switch 144 to be closed and through an obvious circuit the motor 54 is energized and drives through gears 58, 62, 68, and 70 the shaft 72 which reciprocates the vertically movable carriage. At the same time the magnet 108 attracts the tongs associated therewith and the tips thereof come down and force the two oppositely disposed racks 110 and 112 into the same vertical position, the pinion slipping on the shaft. The means then goes through the remainder of the cycle, that is, until the carriage has reached the uppermost vertical position at which point the pin 138 presses against the switch arms and breaks

the switch at 130 and then the motor is deenergized.

The two racks are now in a position as shown in Figure 6, that is, with the two upper extremities lying in the same horizontal plane or leveled. This is repeated for each one of the buttons and of course while six are shown, any number may be supplied, depending upon the requirements of the operator. After each one of the buttons has been set to correspond with a given station, when that button is thereafter depressed the motor will rotate and the attendant tongs will be attracted, forcing the associated racks, which may be at any vertical height, to a leveled position. This will cause the rotation of the pinion in one direction or the other, depending upon how they were set when the button was depressed, and bring into tune the desired station. It is obvious that it is only necessary to depress the desired button 26 for a short period of time until the frame begins its descent, for this closes a holding circuit for the motor through switch 130. At the same time the switch 132 is opened which causes a muting of the loud speaker, and when the frame again reaches its uppermost position the switch 132 is closed, putting the speaker back in the line and opening the motor switch 130. It might also be mentioned at this point that when the frame reaches its uppermost position the two innermost tips 118 of the bell cranks 114 contact the transverse rod 48 to insure that the tongs are in open position upon deenergization so that if the associated magnet is not energized during the next operation the tongs will not contact that particular rack.

We claim:

1. In control mechanism, a rotatable shaft which it is desired to index at different angular positions, a plurality of axially spaced frictionally mounted pinions on the shaft, a plurality of reciprocable racks engaging said pinions to rotate the same, reciprocable means for driving the racks, and selective means for operating only one of the racks and pinion devices at a time.

2. In control mechanism, a rotatable shaft which it is desired to index at different angular positions, a plurality of axially spaced pinions frictionally mounted on the shaft, a pair of oppositely disposed reciprocable racks engaging each to rotate the shaft in either direction, depending upon which of the racks is moved, and means for selectively reciprocating the racks to drive a desired pinion for indexing the shaft.

3. In control mechanism, a rotatable shaft which it is desired to index at different angular positions, a plurality of axially spaced pinions frictionally mounted on the shaft, a pair of oppositely disposed reciprocable racks engaging each pinion to rotate it in either direction, depending upon which rack is moved, members mounted to engage the racks normally biased out of alignment therewith, magnetic means for bringing the engaging means into alignment, means to reciprocate the engaging means and means for selectively energizing the desired magnetic means for a particular angular selection.

4. In a control mechanism for tuning a radio receiving set, a shaft upon which the tuning means are mounted and which it is desired to index at different angular positions, a plurality of pinions mounted on the shaft at axially spaced points, reciprocating racks engaging each pinion to rotate the same for a different setting, a motor for causing rack reciprocation, selective means between the motor-driven means and each rack

and magnetic control means for bringing into engagement the one selected rack.

5. In a tuning control mechanism for a radio receiving set, a tuning shaft that it is desired to index at different points, a plurality of pinions axially spaced on the shaft, means for driving each pinion in either direction to rotate the shaft, magnetic means for selecting which pinion is to be driven and a control panel connected to the 10 magnetic means.
6. In an automatic tuning mechanism for a radio receiving set, a tuning shaft, a plurality of pinions mounted in spaced relation on the shaft, a plurality of racks oppositely disposed for each 15 pinion which normally are set with their ends extending to different distances, means for each pair of racks which may be aligned therewith to force the farthest extending rack until the other rack is engaged to level the pair engaging one 20 pinion which will therefore set the shaft in a given position, magnetic means for causing the alignment and a plurality of selectable switches to cause energization of the desired magnetic means.
- 25 7. In an automatic tuning mechanism for a radio receiving set, a tuning shaft, a plurality of axially spaced pinions on the shaft, a pair of reciprocating racks for driving each pinion, a motor for driving the reciprocating racks, magnetic means for causing only one set of racks to 30 drive and switch means to select which of the magnetic means is to be energized.
8. In an automatic control system for tuning a radio receiving set, a tuning shaft, a motor for 35 rotating said tuning shaft, reciprocating means operated by the motor for turning the shaft, a switch to control initial motor energization and a holding switch actuated by reciprocation of the means to carry the mechanism through a complete cycle.
- 40 9. In an automatic control system for tuning a radio receiving set, a tuning shaft, a plurality of axially spaced pinions frictionally mounted on the shaft, reciprocable racks for driving the pinions different distances, locking means for preventing shaft rotation while the pinions are initially set on the shaft, and motor means for driving the reciprocating means to time or set the pinions.
- 45 10. In an automatic tuning mechanism for a radio receiving set, a tuning shaft, a plurality of axially spaced pinions mounted on the shaft, a pair of reciprocable racks meshing with each pinion, a pair of reciprocable spring biased pivoted arms normally out of alignment with the 50 rack movement and cooperating therewith, means to reciprocate the arms, means to bring the arms into alignment with the racks and remote control means to actuate the last named means.
- 55 11. In a control mechanism, a frame, a shaft 60 rotatably mounted in the frame, a plurality of axially spaced pinions mounted on the shaft, a pair of racks mounted in the frame for reciprocal movement meshing with opposite sides of each pinion, a sub-frame mounted within the frame and movable with respect thereto in alignment with the movement of the racks, means carried by the sub-frame normally out of alignment with the racks but capable of being moved into alignment, and selective means for energizing said means to operate a desired set of racks.
- 65 70 12. In a control mechanism, a pair of rela-

tively movable frames, a rotatable shaft carried by one of the frames, a plurality of axially spaced driving means mounted on said shaft, a plurality of reciprocable means associated with each driving means, means carried by the second frame to selectively engage or pass the reciprocable means upon relative motion of the two frames and means to control the selective means.

13. In a control mechanism, a pair of relatively movable frames, one within the confines of the other, a rotatable shaft carried by one frame, spaced pinions on the shaft, reciprocable racks carried by the same frame and meshing with the pinions, pivoted arms carried by the second frame adapted to engage or pass the ends of the racks upon relative movement of the frames, spring means to maintain said arms in one position, magnetic means to move said arms to engaging position and remote switching means to selectively energize the magnetic means.

14. In a control mechanism, a pair of relatively movable frames, one within the confines of the other, a rotatable shaft carried by one frame, spaced pinions on the shaft, reciprocable racks carried by the same frame and meshing with the pinions, pivoted arms carried by the second frame adapted to engage or pass the ends of the racks upon relative movement of the frames, spring means to maintain said arms in one position, magnetic means to move said arms to engaging position, counterbalancing means on the arms to assist the spring force and remote switching means to selectively energize the magnetic means.

15. In a control mechanism, a frame, a shaft rotatably mounted in the frame, a plurality of axially spaced pinions mounted on the shaft, a pair of reciprocable racks mounted in the frame meshing with each pinion, a pair of spring biased tongs mounted adjacent one end of each pair of racks and adapted to engage the rack ends when in the proper position, a common mounting for all of the tongs, means to reciprocate the mounting in the direction of the length of the racks and magnetic means for each pair of tongs to act against the spring pressure and move the tongs to engage the rack ends and level any desired rack pair.

16. In a control device, a rotatable shaft which it is desired to index to a plurality of desired positions, a plurality of axially spaced pinions mounted on the shaft, a pair of reciprocable racks for each pinion mounted to mesh with diametrically opposite sides thereof, reciprocable means to engage the ends of both racks in a pair and to force the two into alignment whereby the advancing rack acts as a stop to define an index for said shaft.

17. In a control mechanism, a rotatable shaft which it is desired to index to a plurality of angular positions, a plurality of axially spaced pinions frictionally mounted on the shaft, a pair of reciprocable racks for each pinion mounted to mesh with diametrically opposite sides thereof, a plurality of means adapted to selectively engage the ends of each pair of racks, a mount for the last named means, means for reciprocating the mount and means to select one of the first named means for engaging a pair of racks.

ROBERT H. HILL.
BERTRAM A. SCHWARZ.
